CLAIM

(22) Filed: **Jun. 30, 2003**

The ornamental design for a watch casing and portion of a strap, as shown and described.

(51) **LOC (7) Cl. 10-02**

DESCRIPTION

(52) **U.S. Cl. D10/30; D10/38**

FIG. 1 is a perspective view of a watch casing and portion of a strap showing my new design;

(58) **Field of Search D10/1-40, 122-132; 368/280-282, 276-277, 28-30, 285, 239-242, 243-249, 82-84, 41-44**

FIG. 2 is a top plan view thereof;

(56) **References Cited**

FIG. 3 is a left side elevational view thereof;

U.S. PATENT DOCUMENTS

FIG. 4 is a right side elevational view thereof;

D355,376 S * 2/1995 Nakai D10/38

FIG. 5 is a first end elevational view thereof;

D380,967 S * 7/1997 Ludvig D10/30

FIG. 6 is a second end elevational view thereof; and,

D387,677 S * 12/1997 Hanagata D10/30

FIG. 7 is a bottom plan view.

D417,399 S * 12/1999 Sugisawa D10/30

The speckled dots are intended to illustrate a contrast in

D452,169 S * 12/2001 Syoubayashi D10/30

color and/or material used to construct and illustrate the

D472,477 S 4/2003 Sun

claimed invention. The fact that the drawings illustrate dots,
